Chapman Bloom, Jr.

United States Patent Office.

JOHN CARR, OF EMERALD POST OFFICE, OHIO.

Letters Patent No. 92,582, dated July 13, 1869.

IMPROVEMENT IN FENCE.

The Schedule referred to in these Letters Patent and making part of the same.

To all whom it may concern:

Be it known that I, JOHN CARR, of Emerald Post Office, in the county of Adams, and State of Ohio, have invented a new and valuable Improvement in Fences; and I do hereby declare that the following is a full, clear, and exact description of the construction and operation of the same, reference being had to the annexed drawings, making a part of this specification, and to the letters and figures of reference marked thereon.

Figure 1, of the drawings, is a plan view of my invention.

Figure 2 is a detail view.

My invention relates to portable fences; and

It consists mainly in a novel arrangement of devices intended to serve as cheap and effective means for producing the object named.

The letters A, of the drawings, represent a series of short arms or braces, pivoted together as shown, and united at the bottom, by the cross-bar B. These braces and this cross-bar, when united in the manner shown on fig. 2, serve as the posts for my portable fence.

The letter C, of the drawings, represents the bottom board of my fence, the ends of which are cut out, as shown, and forming triangular-shaped wedges, that fit each other closely when in place. These bottom boards respectively rest upon the cross-bar B, in the opening formed by the diagonal position of the lower braces A.

When thus placed in position, these bottom boards give great firmness to the fence.

The letters D represent the rails of my fence. They consist of spars or bars of timber, made pointed at each end, and arranged to pass each other for a short distance in the openings; of diamond-shape, formed by the braces A when in place. When thus placed in said openings, these rails, in conjunction with the bottom board, serve to make the fence strong and firm.

The pivot-pins of my fence are marked *a* on the drawings. They respectively pass through the braces A, as shown, and are in turn pinned in place by the small pins *s*.

This arrangement serves as an economical and ornamental portable fence, easily taken apart, and easily repaired when broken.

What I claim as my invention, and desire to secure by Letters Patent, is—

A portable fence, having braces A, cross-bar B, bottom board C, rails D, and pivot-pins *a*, constructed and arranged substantially as specified.

In testimony that I claim the above, I have hereunto subscribed my name, in the presence of two witnesses.

JOHN CARR.
